UNITED STATES PATENT OFFICE

NATHAN M. LOWER, OF BALTIMORE, MARYLAND, ASSIGNOR, BY MESNE ASSIGNMENTS, TO THE STANDARD STOKER COMPANY INC., OF NEW YORK, N. Y., A CORPORATION OF DELAWARE

STOKER MECHANISM

Application filed June 14, 1924, Serial No. 720,140. Renewed October 9, 1931.

The principal object of the invention is the provision of new and improved stoker mechanism for conveying fuel from the tender to the locomotive.

5 Other and further objects and advantages of the invention will appear from the following description taken in connection with the accompanying drawings, in which

Fig. 1 is a side elevation of a locomotive 10 and its tender, shown more or less diagrammatically, with parts broken away and parts in section;

Fig. 2 is an enlarged partial section on line 2—2 of Fig. 1;

15 Fig. 3 is a vertical section on line 3—3 of Fig. 2;

Fig. 4 is a view similar to Fig. 3 but showing a slightly modified form of the agitating device; and

20 Fig. 5 is a section on line 5—5 of Fig. 4.

On the drawings, the reference character 1 designates a locomotive of any usual or well known construction and 2 the tender therefor. The reference character 3 designates a stoker which may be of any suitable

25 construction, that shown being an improvement on the type disclosed in my Patent No. 1,652,028 granted December 6, 1927, and comprises a trough 4 to the forward end of which

30 is connected an elevator casing or conduit 5 which extends forwardly and upwardly to an opening 6 in the back head 7 of the firebox 8 of the locomotive. The trough 4 is provided with the usual conveyor screw 9 for

35 conveying the fuel from the tender along the trough 4 and forcing the same upward through the conduit or casing 5 onto the distributor plate 90 in front of the steam nozzle 10 which distributes the fuel over the grates

40 of the firebox. A vane provided with a forwardly extending portion 11 and a rearwardly extending portion 12 pivotally mounted at the middle of the upper portion of the elevator and provided with a handle 13 for

45 manually controlling the same is adapted to direct the fuel to either side of the distributor plate to trim the fire at either side of the firebox, as required.

50 Suitable means is provided in the elevator for agitating the fuel in order to prevent

the same from becoming clogged or packed while it is being forced upward through the elevator. As shown in Figs. 1, 2 and 3, a plurality of elevator bands or chains 14 are employed for this purpose. The chains 14 are arranged to move upward on the floor of the elevator 5 at each side thereof by means of sprockets 15 which are rigidly mounted on the power shaft 16. The bands or chains 14 engage idler sprockets 17 and 18 at the upper and lower end of the elevator respectively. The lower run of the bands or chains and the sprockets are protected by a suitable housing 19.

55 The conveyor screw 9 is operated by a motor 20 in any suitable manner. As shown, the screw conveyor 9 is driven from its front end by the shaft 21 thereof which extends through the casing 14a and is provided with a worm gear 22 protected by the housing 23. The motor 20 may be a rotary steam engine 60 having the power shaft 16 journaled in the housing 23 and provided with a worm 25 for engaging said worm gear 22 for operating the stoker.

70 The proportion of water used to the fuel consumed in a locomotive, varies slightly with different grades of fuel, but for all practical purposes with the average grade of fuel and water at a uniform temperature the ratio may be considered as a fixed quantity. For this reason it is desirable to operate the pump in timed relation with the stoker and in order to insure this movement the pump 75 25a is located adjacent to the motor 20.

80 A rotary pump preferably of the centrifugal type is employed. The pump is located on the rear of the locomotive below the cab deck whereby the same is not only in convenient position to be operated from the stoker motor but is also in an advantageous operating position for efficient operation since water may be supplied to the pump from the tank with little or no suction. The pump may be mounted on, or have its operating shaft connected to, the power shaft 16, whereby the pump is operated directly from the motor shaft, in which event it may be desirable or necessary to employ a multiple 85 stage pump.

Water is supplied to the pump from the tank 27 through suitable pipe and flexible hose connection 28, which may be provided with a valve 29 for regulating the supply of water to the pump. The pump forces the water into the boiler through any suitable conduit. As shown, it is forced through a pipe 30 into the heater 31 where the water is heated preparatory to its introduction into the boiler 32. From the heater, the water, under pump pressure, passes into the boiler through the pipe 33, as conventionally shown in Fig. 1.

In the operation of the device steam is admitted to the motor or engine through the pipe 33a which operates the motor 20 and through it operates both the stoker 3 and pump 25a for supplying fuel and water to the locomotive. A valve 26a enables the fireman to regulate the supply of steam to the engine 20 to control the fuel and water supply to meet the locomotive requirements.

While the power shaft 16 is shown and described as being operated by a rotary engine, it is understood that it may be operated by any other type of engine or motor.

A modified form of elevator is disclosed in Figs. 4 and 5. In this construction, elevator mechanism such as the short screw section 34 is provided in the casing or conduit 41 intermediate the ends thereof for assisting in conducting the fuel upwardly through said conduit or casing and to prevent the fuel from becoming packed or jammed. This screw performs the same function as the chains 14 heretofore described in connection with Fig. 3. Suitable means is provided for operating the elevator screw section. As shown, it is operated by means of an annular worm gear 35 rigidly connected to the screw 34 as by being connected at one side to the flight of the screw as at 36 and at the other to one or more standards 37 rigidly connected to said screw. The periphery of the worm gear 35 is adapted to be received in a groove 38 formed by offsets in the meeting edges 39 and 40 of the two sections of the elevator casing 41. The worm gear 35 is operated from the worm 42 which is rotated through suitable flexible gearing 43 from the power shaft 16.

It will be understood that various changes in the form, size, construction, composition and arrangement of the several parts may be resorted to without departing from the spirit and scope of my invention; hence I do not wish to limit myself strictly to the structure herein set forth.

I claim as my invention:

60 In combination, a locomotive provided with a firebox having a backwall with a firing opening therein, a tender for said locomotive, a transfer conduit located beneath the floor of the tender, a single substantially straight 65 inclined elevator casing communicatively

joined in end to end relation with and extending upwardly and forwardly from the front end of said transfer conduit to the lower portion of said firing opening, the upper forward end of the elevator casing 70 opening directly into said lower portion of the firing opening, a pressure fluid distributing means arranged in the lower portion of said firing opening to receive fuel directly from the upper end of said elevator casing, 75 a conveyor screw in said transfer conduit for conducting fuel along said conduit and forcing the same upwardly through said elevator casing, and means separate and apart from said screw operating within said elevator casing intermediate the ends thereof to prevent impacting of the fuel therein and to assist in advancing the fuel through the elevator casing to the distributing means.

NATHAN M. LOWER.
